Primary Examiner — Kendra Leslie Hamilton*Assistant Examiner* — Amanda Christensen(74) *Attorney, Agent, or Firm* — Timothy G. Ackermann(57) **CLAIM**

The ornamental design for an electrical outlet, as shown and described.

DESCRIPTION

FIG. 1 is a top, front, left side isometric view of an electrical outlet, showing my new design.

FIG. 2 is a bottom, front, left side isometric view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a front elevation view thereof.

FIG. 8 is a rear elevation view thereof.

FIG. 9 is a front, left side oblique view thereof; and,

FIG. 10 is a front, right side oblique view thereof.

The broken lines depict portions of the electrical outlet that form no part of the claimed design. All text and safety labeling depict unclaimed subject matter and form no part of the claimed design.

1 Claim, 9 Drawing Sheets(56)
